UNITED STATES PATENT OFFICE.

FLETCHER C. ROOD, OF PORTLAND, OREGON.

ROTARY PUMP.

1,240,489.

Specification of Letters Patent. Patented Sept. 18, 1917.

Application filed July 20, 1914. Serial No. 851,925.

To all whom it may concern:

Be it known that I, FLETCHER C. ROOD, a citizen of the United States, who resides in the city of Portland, county of Multnomah, 5 and State of Oregon, have invented certain new and useful Improvements in Rotary Pumps, of which the following is a specification.

My intention relates to rotary pumps of 10 the kind having coöperating rotary impellers or vanes secured within a suitable casing upon parallel shafts. It has for its principal object to provide in such a pump a construction in which each of the rotary 15 impellers alternately rotates a half revolution and then stands still while a companion impeller rotates a half revolution, said impellers thus operating at all times to form a partition or division across said casing 20 chamber, with one portion of the chamber serving as an inlet or receiving chamber, and the other portion thereof as a discharging chamber. Thus by making possible this intermittent revolution of the impeller and 25 alternating them, the chamber within the casing is divided at all times into two non-communicating chambers, one of which is a receiving chamber and the other is a discharging chamber.

In order that others may understand my 30 invention, I have shown one practical embodiment thereof in the accompanying sheet of drawings, which I will now describe.

Figure 1 is a top plan view of one form 35 of the invention with a portion of the casing broken away and parts shown in section;

Fig. 2 is an end view thereof showing one kind of gearing connection with which I am 40 able to accomplish the alternate intermittent movements of the impellers or vanes;

Fig. 3 is a sectional view taken on line 45 3—3 of Fig. 1, showing the inside arrangement of the impellers, and also the inlet and exhaust ports; and

Figs. 4 and 5 show one pair of the coöperating intermittent gears for effecting the alternate intermittent drive of the impeller.

Referring now to the drawings, 1 designates a casing, here shown of elliptical form 50 in cross section, with inlet and discharge ports, as 2 and 3. Mounted within said casing are two impellers 4 and 5, shown more clearly as to their form and coöperative arrangement in Fig. 3, which shows the end view thereof. Certain of the outer

portions or edges of these impellers are shown rounded, as at 4^a and 5^a, while other portions thereof, as from the bulge or middle to the end are shown straight, as at 4^b and 5^b, said surfaces being shaped so as to give the best bearing engagement therebetween in their rotative movements. Thus assuming that impeller 5 is standing still in the crosswise position shown in Fig. 3, 60 and that impeller 4 is revolving in the direction indicated by the arrow, as soon as impeller 4 reaches the position shown in dotted lines, its bearing surface at 4^b, nearest its shaft, engages the rounded outer surface 70 5^a of impeller 5, with the greatest leverage, and gives to impeller 5 an initial movement, which is continued by the gear connection hereinafter again referred to. The impeller 4 then assumes a crosswise position and 75 stands still until the opposite end of the impeller 5 makes a half revolution and gives to it a starting movement, which is continued by the gear connection, which I will now describe.

Each of the impellers 4 and 5 is provided upon its carrying shaft, outside the casing 1, with an intermittent gear member, as 6 and 7, respectively, adapted to mesh, respectively, with two intermittent driving 85 gears, as 8 and 9, mounted upon a driving shaft 10, which may be driven by hand, as with a crank 11, or by any power mechanism desired.

The intermittent gears 6 and 7, mounted 90 upon the impeller shafts are provided at their opposite sides with smooth concaved portions, as 6^a and 7^a, instead of a continuation of their teeth, while the gears 8 and 9 are provided with teeth only for a portion 95 of their circumference and are left full or solid in conical form for the balance thereof, as at 8^a and 9^a.

Assuming that shaft 10 is being revolved and with it gears 8 and 9, the toothed portion of the gear 8 is in mesh with the toothed portion of the gear 6 and is therefore driving gear 6 and its impeller 4, while a solid portion of gear 9 is turning in one of the concaved portions 7^a in gear 7, thus leaving 105 gear 7 and its impeller 5 standing still. Under this action, impeller 4 moves to the position shown in dotted lines, Fig. 3, where it engages impeller 5 and imparts to it an initial movement which operates to 110 turn its gear 7 sufficiently to bring its teeth into mesh with a toothed portion of the

gear 9, which has reached that point, which connection continues the movement of the impeller 5. In the meantime the concaved portion 6^a of gear 6 and the solid portion 5 8^a of gear 8 have moved together, leaving gear 6 and its impeller 4 standing in a cross-wise position until impeller 5 makes another half revolution and its opposite end engages impeller 4 and gives to it an initial move- 10 ment sufficient to move its gear 6 again into driving engagement with the toothed portion of gear 8. Thus by revolving shaft 10 and the gears 8 and 9 continuously, the gears 6 and 7 are given alternately a half revolution, and impart the same movement to the 15 impellers or vanes 4 and 5, which operate to cause an inrush of fluid through inlet 2, and to force it out through discharge port 3, in a manner well understood.

20 I am aware that slight changes can be made in the embodiment of my invention here shown for purposes of illustration without departing from the spirit thereof, and that different driving connections can 25 be used to impart the alternate intermittent movement to the impellers, and I do not, therefore limit myself to the form here shown, except as I may be limited by a broad interpretation of the hereto appended 30 claims.

I claim,—

1. In a rotary pump, a casing with inlet and discharge ports, rotary impellers mounted to revolve upon independent parallel 35 shafts spaced apart therein, and means for driving said impellers with an intermittent and alternating movement, said impellers being adapted to have a rolling contact with each other as they come together.
- 40 2. In a rotary pump, a casing provided with inlet and discharge ports, two rotary impellers having convexed faces and mounted to turn about parallel axes within said casing, and driving connections adapted to drive said impellers alternately for a portion 45 of a full revolution at a time.
- 45 3. In a rotary pump, a casing having inlet and exhaust ports, rotary impellers mounted upon spaced parallel shafts therein 50 in coöoperative relationship with each other, a driving member adapted to be continu-

ously driven, and intermittent driving connections from said driving member to said impellers designed to alternately drive them a portion of a revolution at a time, said impellers having rounded contacting faces and adapted to have intermittent rolling engagement with each other, for the purpose specified. 55

4. A rotary pump of the character referred to comprising in combination, a casing provided with inlet and discharge ports, two coöperating impellers rotatably mounted to turn about parallel, spaced axes therein and adapted to have a rolling bearing 60 engagement one with the other, a driving member adapted to be continuously driven, and intermittent driving connections from said member to said impellers adapted to alternately drive them for a portion of a 65 revolution only at one time.

5. In a rotary pump, the combination with the casing and the coöperating impellers revolvably mounted therein, of a driving mechanism comprising a continuously driven member, and intermittent gear members connecting said impellers with said driven member and arranged to impart alternately to said impellers a part of a full revolution, each impeller being adapted 70 to give to the other an initial movement to put its gear members into action. 75

6. In a rotary pump, the combination of a casing provided with inlet and discharge openings, two rotary impellers mounted 80 therein in coöperating relationship with each other, a driving shaft, intermittent gear members mounted on said shaft and intermittent gear members mounted on said impellers, said gears being connected with 85 each other in pairs and said pairs being adjusted to alternately and intermittently drive said impellers for a portion of a revolution at a time, one impeller being adapted to engage and impart an initial movement 90 to the other, substantially as described. 95

Signed at Portland, Multnomah county, Oregon, this 14th day of July, 1914.

FLETCHER C. ROOD.
